UNITED STATES PATENT OFFICE.

WILHELM FRIMAN, OF NEWPORT NEWS, VIRGINIA.

SAFETY DEVICE FOR ELEVATORS.

1,108,355.

Specification of Letters Patent. Patented Aug. 25, 1914.

Application filed September 17, 1913. Serial No. 790,328.

To all whom it may concern:

Be it known that I, WILHELM FRIMAN, a subject of the Czar of Russia, residing at Newport News, in the county of Warwick 5 and State of Virginia; have invented certain new and useful Improvements in Safety Devices for Elevators, of which the following is a specification, reference being had to the accompanying drawings.

10 This invention relates to new and useful improvements in elevators and more particularly to safety devices therefor and the primary object of the invention is to provide a device of this character which will positively prevent the loss of life of the occupants of the elevator in case the operating cables therefor are broken.

15 A further object of the invention resides in providing an elevator cage having a movable floor therein which directly operates the safety devices.

20 A still further object of the invention resides in providing a device which is simple and durable in construction, inexpensive to manufacture and one which will be very efficient and useful in operation.

25 With these and other objects in view, the invention consists in the novel features of construction, combination and arrangement 30 of parts as will be hereinafter referred to and more particularly pointed out in the specification and claims.

35 In the accompanying drawings forming a part of this application, Figure 1 is a vertical section through the elevator cage in place in the shaft. Fig. 2 is a similar view taken at right angles to the plane of Fig. 1. Fig. 3 is a diagrammatic view of the cam action of the device. Fig. 4 is a detail elevation 40 partly in section of the springs used in the device. Fig. 5 is a diagrammatic view showing the relation of the cams and gears in use in the device. Figs. 6 and 7 are detail elevations of the different sets of gears in 45 the device. Fig. 8 is a fragmentary horizontal section of the device showing the manner in which the elevator cage is braced in the shaft; Fig. 9 is a diagrammatic view showing the position of the parts of the device first, when the elevator is in its operative 50 position in the cage; and second, when the elevator is falling after a cable has been broken, and Fig. 10 is a detail plan view of the connection between the turnbuckle and 55 spring member in the device.

In describing my invention, I shall refer to the drawings in which similar reference characters designate corresponding parts throughout the several views and in which—

1 indicates an elevator cage or car operatively mounted in the shaft 2. This car or cage 1 is provided with a door-way 3, and mounted for sliding movement between rails 4 which are arranged in the inner corners of the car 1, is a platform 5, said platform having grooved rollers 6 arranged at the corners thereof for coöperation with the rails 4. The car or cage proper which is often termed a shell, is guided in the shaft 2 between a pair of side rails or tracks 8 mounted on the sides of said shaft, said shell or car being provided with pairs of upper and lower keepers 9 slidably receiving the rails or tracks 8 therein and through the medium of this construction there will be no lateral or torsional movement of the device as the same is raised and lowered in the shaft.

65 The platform 5, which forms a movable bottom in the elevator car or cage 1, is suspended in the latter by means of rods 10, said rods having coil springs 11 engaged with the upper ends thereof and chains engaged with said coil springs, said chains extending loosely through the top of said 70 car or cage 1. The springs 11 are tensioned by the movable platform 5 and, should the cable or rope 21 break, serve to throw the 75 brakes or cams 22 into operative position, as will hereinafter be more fully set forth. In 80 order that the passengers of the car or cage may not observe these rods, springs, and chains, covering plates or walls 7 are provided which depend from the top of the car or cage 1 to points adjacent the normal position of the platform 5.

85 Mounted on the side edges of the top of the car or cage 1 are the bearing members 13 which receive therethrough a pair of shafts 14 which are designed to oscillate in 90 said bearings. Mounted on the shafts adjacent the ends of the same are the combined gears and pulleys 15, the gear portions of which are meshed with one another and the pulley portions of which receive thereon the 95 chains 12, said chains being also secured to said combined gears and pulleys. It will be seen from this construction that the platform is movable within the car 1, and when moved downwardly, is adapted to cause the 100

105

110

shafts 14 to be rotated in opposite directions through the medium of the gear portions of the combined gears and pulleys 15.

Arranged in connection with each of the 5 shafts 14 are shaft reversing devices 16, the same being helical springs which are respectively secured at one end to the shafts and coiled therearound, the other ends of the springs being connected together by means 10 of the turnbuckles 17. The springs tend to rotate the shafts in the same direction as the combined gears and pulleys 15, and through the medium of the turnbuckles 17, it will be seen that the tension of such springs may be 15 readily adjusted, for a purpose to be seen from the description presently to follow. Also mounted on the shafts 14, about centrally thereof, are the additional combined pulleys and gears 18, the gear portions of 20 which are meshed with one another, and the pulley portions of which have extending thereover the chains 19, the latter being secured at their lower ends to said members 18. The chains 19 tend to converge upwardly and are connected to a linking member 20 which is suspended from the lower end of a cable or rope 21, the latter being connected to the means for raising and lowering the car. Rigidly mounted on the 25 outer ends of the shafts 14 are the cams 22 which are arranged on each side of the aforesaid rails 8 and, in the normal position of the device, these cams are slightly spaced from said rails. The tendency of these 30 springs 16 is to turn the shafts 14 in such a direction as to cause the cams 22 to bind tightly against the rails 8 but the weight of the elevator and its adjunctive parts, with 35 or without passengers therein, pulling 40 downwardly on the suspension means, over-balances the tension of said springs. The shafts 14 are, therefore, rotated sufficiently through the medium of the members 18 and the chains 19 which are connected with the 45 members 18 and the suspension means, to dispose the cams or what may be termed clutch members, to their ineffective positions with respect to the rails 8. This is the normal position of said cams and shafts in the 50 movement of the elevator car in the shaft. Should it occur, however, from any cause whatsoever, that one of the chains 19 or the suspension cable 21 become severed, thereby releasing the normal pull or force on the 55 combined pulleys and gears 18, the springs 16 will immediately become effective and being under tension tend to rotate the shafts 14 in the opposite direction to which they had been disposed by the members 18. The 60 disposition of these shafts in the last mentioned direction will, obviously, cause the cams or clutch members 22 to become effective and bind tightly against the rails 8. In this manner, it will be seen that the elevator 65 car may only drop a very slight dis-

tance, such distance being measured in inches. The position of the parts with respect to one another in their positions before and after the cams are in their effective position, may be seen from the showing 70 made in the diagrammatic view indicated as Fig. 9. In view of the spring suspension of the platform in the elevator car, which directly supports the passengers, it will be seen that no undue jar will occur as the suspension means is severed and the car tends to descend in the shaft. The construction of this safety device is such as to stop the complete device in its descension almost immediately upon the severing or breaking of 75 the suspension cable or any part in connection therewith.

From the foregoing description of the construction of my improved device, the operation thereof will be readily understood, and it will be seen that I have provided an improved safety device for elevators which will be obviously effective in every respect. It will further be seen that the device is one which is simple and durable in construction, inexpensive to manufacture, and very efficient and useful in operation.

While I have particularly described the elements best adapted to perform the functions set forth, it is obvious that various changes in form, proportion and in the minor details of construction may be resorted to, within the scope of the appended claims, without departing from the spirit 90 or sacrificing any of the principles of the invention.

Having thus described this invention, what is claimed is:

1. The combination with an elevator shaft provided with tracks, a car arranged to engage the tracks, and suspension means for the car; of a pair of shafts mounted for partial rotation on the top of the car, three pairs of intermeshing gears carried by the 105 shafts, independent flexible connections between the intermediate pair of gears and the suspension means connected to rotate the shafts in one direction, reversing springs connecting the shafts, a movable platform arranged in the car, connections between the terminal pairs of gears and the platform arranged to rotate the shafts in the same direction as the springs, and track clutches carried by the ends of the shafts and disposed on opposite sides of the tracks and arranged to grip the tracks when the shafts are rotated by the springs and platform by the breaking of the suspension means.

2. The combination with an elevator shaft provided with tracks, a car arranged to engage the tracks, and suspension means for the car; of a pair of horizontal shafts mounted for partial rotation on the top of the car and projecting beyond the sides 120 130

thereof, three pairs of intermeshing gears carried by the shafts, independent flexible connections between the intermediate pair of gears and the suspension means connected to rotate the shafts in one direction, reversing springs connecting the shafts, means for adjusting the tension of the springs, a movable platform mounted within the car, yielding connections between the 10 terminal pairs of gears and the platform arranged to rotate the shafts in the same direction as the springs, and means carried by the outer ends of the shafts and arranged to engage frictionally with the tracks when 15 the shafts are rotated by the springs and platform.

3. The combination with an elevator shaft provided with tracks, a car arranged to engage the tracks, and suspension means for the car; of a pair of horizontal shafts mounted for partial rotation on the top of the car and projecting beyond the sides thereof, three pairs of intermeshing combined gears and pulleys mounted on the 20 shafts, independent flexible connections between the intermediate pairs of pulleys and the suspension means connected to rotate the shafts in one direction, adjustable reversing springs connecting the shafts, a movable 25 platform arranged within the car, yielding connections between the platform and the two terminal pairs of pulleys arranged to rotate the shafts in the same direction as

the springs, and cams carried by the outer ends of the shafts and arranged to engage 35 with the tracks when the shafts are rotated by the springs and platform.

4. The combination with an elevator shaft provided with tracks, a car arranged to engage the tracks, and suspension means for 40 the car; of a pair of horizontal shafts mounted for partial rotation on the top of the car and projecting beyond the sides thereof, three pairs of intermeshing combined gears and pulleys carried by the 45 shafts, independent flexible connections between the intermediate pair of pulleys and the suspension means connected to rotate the shafts in one direction, adjustably connected reversing springs connecting the 50 shafts, a movable platform, resilient connections between the terminal pairs of pulleys and the platform, arranged to rotate the shafts in the same direction as the springs, and pairs of cams carried by the terminals 55 of the shafts and disposed on each side of the tracks, and arranged to be thrown into engagement therewith by the reversing springs and platform upon breakage of the 60 suspension means.

In testimony whereof I hereunto affix my signature in the presence of two witnesses.

WILHELM FRIMAN.
